UNITED STATES PATENT OFFICE.

HERBERT S. HUMPHREY, OF KALAMAZOO, MICHIGAN.

WATER-HEATER.

1,129,293.

Specification of Letters Patent. Patented Feb. 23, 1915.

Application filed November 26, 1912. Serial No. 733,577.

To all whom it may concern:

Be it known that I, HERBERT S. HUMPHREY, a citizen of the United States, residing at Kalamazoo, Michigan, have invented certain new and useful Improvements in Water-Heaters, of which the following is a specification.

This invention relates to improvements in water heaters.

10 The main objects of this invention are, first, to provide an improved controlling mechanism for water heaters and the like. Second, to provide an improved valve mechanism for water heaters and the like which is simple and economical and not likely to get out of repair in use.

Further objects and objects relating to structural details, will definitely appear from the detailed description to follow.

20 I accomplish the objects of my invention by the devices and means described in the following specification.

The invention is clearly defined and pointed out in the claims.

25 A structure which is a preferred embodiment of my invention is clearly illustrated in the accompanying drawing forming a part of this specification, in which:

Figure I is a detail side elevation of a structure embodying the features of my invention. Fig. II is a detail side elevation of my improved controlling mechanism removed from the heater. Fig. III is a plan view thereof. Fig. IV is a detail side elevation partially in vertical section on a line corresponding to line 4-4 of Fig. III. Fig. V is a detail side elevation partially in vertical section on a line corresponding to line 5-5 of Fig. III. Fig. VI is a detail vertical section on a line corresponding to line 6-6 of Fig. V, showing details of the adjustable fulcrum 35. Fig. VII is a vertical transverse section through the fuel valve casing on a line corresponding to line 7-7 of Fig. V. Fig. VIII is a detail section on a line corresponding to line 8-8 of Fig. V.

In the drawing similar reference characters refer to similar parts throughout the several views, and the sectional views are taken looking in the direction of the little arrows at the ends of the section lines.

Referring to the drawing, the heater illustrated is of the coiled type the coils 1 being arranged within the casing 2. The water is delivered to the upper end of the coils through the pipe or conduit 3, and is dis-

charged from the lower end of the coils through the pipe or conduit 4. In the structure illustrated, the coils are heated from the gas burners 5. The water is delivered to the conduit 3 through the valve casing 6 which is provided with an inlet nipple 7 having a regulating valve 8. The conduit 3 is connected to the valve casing through the port 9. The water inlet valve 10, here shown mainly in conventional form, is of the piston type and adapted to be automatically opened by the pressure of the inlet water when the water is drawn from the heater, thereby reducing the pressure within the heater or system or unbalancing the pressure. The system or draw-off pipe 11 is connected to the passage 12 of the water valve casing 6, the passage 12 being connected by the thermostat tube 13 to the discharge conduit 4 of the coils. This connection of the draw-off pipe or system 11 through the passage 12 in the valve casing 6 is mainly a matter of convenience. The valve 10 is normally closed by the spring 14. The gas valve casing 15 is connected to the water valve casing 6 by means of the yoke 16, the ends of the yoke being adapted to receive the studs 17 and 18 on the valve casings 15 and 6 respectively. The studs are threaded to receive the cap-like members or nuts 19 and 20. The gas supply pipe is connected to the nipple 21 of the gas valve casing. The valve casing is provided with a nipple 24 to which the gas burner conduit 25 is connected. The pilot conduit 26 is connected to the valve casing 15. As the details of the pilot form no part of the present invention, they are not illustrated herein. The gas valve 27 is held normally seated by the spring 47. The cock 22 is tapered and is drawn into its seat by means of the spring 28 on the screw 29. See Fig. IV. The gas valve is opened through the thermostat, the thermostat being rendered operative by the actuation of the inlet valve 10 by water passing to the heater, so that the gas valve is opened only when the valve or water actuated member 10 is actuated as by the drawing of water from the heater. The thermostat members 30 and 31—see Fig. V—are arranged in the thermostat tube 13 which is connected to the heater as described, so that the thermostat is controlled by the water of the heater. The thermostat member 31 acts upon the lever 32 fulcrumed at 33, as shown in Fig. V. The lever 32 acts upon the lever 34

mounted upon the adjustable fulcrum 35. The fulcrum 35 is movably supported in a socket-like seat 36 on the side of the valve casing 15. Below the fulcrum 35, is a cam 37 carried by the rock-shaft 38. The cam is arranged in a bearing 39, as shown in Fig. V. A friction reducing roller 40 is provided for the movable fulcrum 35. The rock-shaft 38 is provided with an arm 41 to which the link 42 is pivoted at 43. The outer end of this link is supported by the supporting link 44, the lower end of which is engaged by the stem 45 of the valve 10, so that when the piston valve 10 is actuated by the water, the cam 37 is actuated to raise the fulcrum 35, thus rendering the operating connections for the thermostat to the gas valve operative. The lever 34 is operatively associated with the stem 46 of the gas valve 27, the stem being provided with a shoulder 48 against which the bearing washer 49 rests. The lever 34 is slotted at 50 to receive the valve stem. See Fig. VIII. The cam 37 is returned to its normal position by means of the spring actuated plunger 51 which engages the link 44. The plunger 51 is arranged through the end of the cap member 20 and provided with a disk-like head against which the spring 52 bears. With the parts thus arranged, when the water valve is returned to its initial position before the discontinuance of the flow of water to the heater, the plunger returns the link 44 to its initial position and through the connection described, the fulcrum adjusting cam. With the parts thus arranged, when the water is drawn from the heater, the unbalancing of the pressure opens the valve 10 and simultaneously actuates the fulcrum member 35 so that, when the temperature of the water passing through the heater is below a predetermined degree, the gas valve is opened through the thermostat. The thermostat, with its connections thus positioned, operates to control the gas valve in the usual manner. When the drawing of water from the heater ceases, the gas valve is immediately closed by its springs, owing to the fact that the means for holding it open, namely, the thermostat and fulcrum member, have been returned to normal position.

The plunger 51 and the valve stem are provided with cap-like bearing members 53 between which the lower end of the swinging link 44 is arranged.

I am aware that very considerable variation from my invention in structural details are possible without departing from my invention, but as such variations will undoubtedly be readily understood from the disclosure made by those skilled in the art to which this invention relates, I have not attempted to illustrate or describe the same herein. I desire to be understood as claiming

my improvements specifically in the form illustrated, as well as broadly within the scope of the appended claims.

Having thus described my invention, what I claim as new and desire to secure by Letters Patent is:

1. The combination with a water heater comprising a water container and heating means, of a fuel valve, a water valve, means for normally closing said valves, a thermostat, operating connections for said thermostat to said fuel valve comprising a lever, a movable member constituting a fulcrum for said lever when actuated by said thermostat, a seat for said member, a cam by which said member is supported in its said seat, a rock shaft on which said cam is mounted, an arm on said rock shaft, a link actuated by said water valve connected to said arm, and a spring for returning said cam to its initial position.

2. The combination with a water heater comprising a water container and heating means, of a fuel valve, a water valve, means for normally closing said valves, a thermostat, operating connections for said thermostat to said fuel valve comprising a lever, a movable member constituting a fulcrum for said lever when actuated by said thermostat, a seat for said member, a cam by which said member is supported in its said seat, a rock shaft on which said cam is mounted, actuated by said water valve, and a spring for returning said cam to its initial position.

3. The combination with a water heater comprising a water container and heating means, of a fuel valve, a water valve, means for normally closing said valves, a thermostat, operating connections for said thermostat to said fuel valve comprising a lever, a movable member constituting a fulcrum for said lever when actuated by the thermostat, and a cam arranged to act on said member, said cam being actuated by said water valve.

4. In a water heater, the combination with a water heater comprising a water container and heating means, of a fuel valve, a water valve, means for normally closing said valves, a lever acting on said fuel valve, a thermostat mechanism including a member acting on said lever, a movable member acting on said lever and constituting a fulcrum therefor when the same is acted upon by said thermostat, and operating connections for said water valve to said movable member whereby the same is actuated by the opening of the valve, the combined action of the water actuated valve and thermostat being required to open the gas valve.

5. The combination of a water heater comprising a water containing and heating means, of a fuel valve, a water valve, a thermostat, operating connections for said

- thermostat to said fuel valve comprising a lever, and a movable member constituting a fulcrum for said lever when actuated by said thermostat, said movable member being actuated by said water valve whereby the thermostat is operative to open the gas valve only when the water valve is opened.
6. A controlling device for water heaters comprising in combination, a water valve, a gas valve, means for normally closing said valves, a thermostatic control means for said gas valve comprising a lever, a movable member constituting a fulcrum for said lever when it is actuated by said thermostatic controlling means, and operating connections for said water valve to said movable member.
7. The combination of a water heater comprising a water container and a heating means therefor, a thermostatic controlling means for said heating means governed by the water of the heater and comprising a lever member, a member coacting as a fulcrum when said lever member is actuated by said thermostat, and a water actuated member having operative connection with said movable member.
8. A controlling device for the heating means of water heaters, comprising a water container and heating means, a gas valve, a thermostatic controlling means governed by the water of the heater and comprising a lever, a water actuated member, and a member actuated by said water actuated member constituting a fulcrum for said lever when the same is actuated by said thermostat whereby said thermostat and water actuated means coact in operating the gas valve.
9. The combination with a water heater comprising a water container and heating means, of a water valve, a gas valve, means for normally closing said valves, a thermostatic controlling means for said gas valve comprising a thermostat lever, a movable member constituting a fulcrum for said lever when actuated by the thermostat, and operating connections for said water valve to said member whereby said member is moved to support the lever in operative position when the water valve is opened.
10. The combination with a water heater comprising a water container and heating means, of a fuel valve, a water actuated
- member, a thermostat, a thermostat lever, a movable member constituting a fulcrum for said lever when it is actuated by said thermostat arranged to normally support the lever in inoperative position, and connections for said water actuated member to said movable member whereby it is moved to support the lever in operative position when the water valve is open.
11. The combination of a water heater comprising a water container and heating means therefor, of a thermostatic controlling means for said heating means governed by the water of the heater and comprising a lever member, a movable member coacting with said lever member as a fulcrum when said lever member is actuated by the thermostatic means, and a water actuated member having operative connection with said movable member whereby the heating means is controlled by the combined action. 75
12. In an automatic heater, the combination with a water heater comprising a water container and heating means, of a gas valve therefor, a power transmitting lever arranged to operate said gas supply valve, and two power applying mechanisms for said lever, each adapted to act as the lever-fulcrum when the other is in operation, one of said mechanisms including a thermostat and the other a water actuated motor, the thermostat being effective in opening the valve only when the motor actuated member is actuated. 80
13. In an automatic water heater the combination of a water heating conduit, a burner, a gas supply valve therefor, a power transmitting lever arranged to operate said gas valve, two power applying mechanisms for said lever each adapted to act as the lever's fulcrum when the other is in operation, one of said mechanisms including a thermostat actuated by the temperature of the water in said conduit, whereby the movement of either the water motor or the thermostat varies the effective action of the other upon said valve. 95

In witness whereof, I have hereunto set my hand and seal in the presence of two witnesses.

HERBERT S. HUMPHREY. [L. 5.]
